UNITED STATES PATENT OFFICE.

JACOB WEBER, OF NEW YORK, N. Y., ASSIGNOR TO STANDARD COMFORT WINDOW CORPORATION, OF NEW YORK, N. Y., A CORPORATION OF NEW YORK.

SLIDING-SASH WINDOW.

Application filed December 29, 1920. Serial No. 433,768.

To all whom it may concern:

Be it known that I, JACOB WEBER, a citizen of Germany, residing at New York, county of New York, and State of New York, have invented certain new and useful Improvements in Sliding-Sash Windows, of which the following is a specification.

My invention relates to windows of the sliding-sash type, and is a further development of the construction disclosed in my pending application for Letters Patent Serial No. 401,372, filed in the United States Patent Office on August 5, 1920. The object of my present improvements is to simplify the construction shown in said earlier application and to secure certain advantages in operation, as will appear from the description following hereinafter.

A preferred embodiment of my present invention is illustrated by the accompanying drawings, in which Fig. 1 is an elevation of the complete window as seen from the inside, with the sashes in the closed position; Fig. 2 is a vertical section of the window frame, the sashes being omitted; Figs. 3 and 4 are enlarged horizontal sections on lines 3—3 and 4—4 respectively of Fig. 1; Fig. 5 is a view somewhat similar to Fig. 2, but showing the sashes in position, with the lower sash swung inward for ventilation; Fig. 6 is a similar view showing the lower sash raised and the upper sash lowered and swung inward; Fig. 7 is a horizontal section on line 7—7 of Fig. 5; Fig. 8 is an enlarged face view showing a lower corner of the lower sash with a locking and pivot bolt attached thereto; Fig. 9 is an edge view looking in the direction of the arrow 9 in Fig. 8; Fig. 10 is an enlarged detail view, looking from the inside, and showing a lower corner of the upper sash, in the raised position, together with the adjacent portions of the frame. Fig. 11 is a vertical section on line 11—11 of Fig. 10, the lower sash being shown in tight engagement with the upper sash; Fig. 12 shows the frame parts in substantially the same position as in Fig. 10, but the upper sash is shown down, and the lower sash up; Fig. 13 is a vertical section on line 13—13 of Fig. 12; and Fig. 14 is a partial view from above, looking at the lower sash in the direction of the arrow 14 in Fig. 5.

The window frame illustrated herein com-

prises a bottom member 20, vertical boxes 21, 22 at each side which contain the sash weights 23, an upper member 24 at the outer side of the window, and a horizontal box or chamber 25 at the top, on the inner side of the window, the lower edges of said box being flush with the upper edges of the opposing walls 21', 22' of the side boxes 21, 22. On said opposing walls are secured, toward the outside of the window, relatively wide vertical strips 26 extending the full height of said walls, and on the opposing faces of the strips 26, at their outer edges, are secured narrower strips 27, likewise extending the full height of the walls 21', 22'. Along the inner edges of said walls, at the upper portions thereof, are secured vertical strips 28 and at the lower portions thereof movable vertical strips 29 (for instance strips mounted on vertical hinges 30) which in one position (Figs. 1, 3, 6, and 10 to 13) will lie in the continuation of the upper strips 28, while in another position (Figs. 2, 5 and 7 and dotted lines in Fig. 3) they will be out of the way so as to clear the path for the inward swinging of the lower sash, as described hereinafter. When thus aligned, the strips 28, 29 form the inner walls of the guideways for the lower sash 31, the outer walls of said guideways being formed by the strips 26, and the side walls by parts of the members 21', 22'. At the sides, toward the outside of the window, the vertical members of the lower sash are recessed, as indicated at 32, thereby forming chambers to receive the cords or chains 33 passing over the corresponding pulleys 34 to the respective sash weights 23. The lower ends of these chains are secured to plates 35 pivoted at 36 to the side members 37 of L-shaped plates secured to the lower sash 31 near its bottom corners. The inner members 38 of said L-shaped plates have aligning horizontal slots 39 (see Figs. 1 and 8) in which are movable studs 40 rigid with transversely movable pivot and locking bolts 41 adapted to be projected into recesses 42 of the walls 21', 22'.

At its bottom, the lower sash 31 has a transverse groove 43 which is adapted to contain a rounded horizontal bar or strip 44 projecting from the bottom member 20. On its rear face, the sash 31 has two vertical grooves 45 adapted to receive edgewise, metal strips 46 suitably secured to the strips

100 105 110 115

26, but only at the lower portions thereof. When the lower sash 31 is moved up, its rear face will be guided partly by the strips 26, and partly by narrow strips or beads 47 secured to the opposing faces of the strips 26, at their upper portions only. The strips 46 and 47 overlap partly, as shown best in Fig. 2.

10 In the box or chamber 25 is movable vertically a horizontal board 48, provided at its end with notches guided along vertical ridges 49. In its normal position (Figs. 2 and 5), said board rests on the upper ends of the walls 21, 22 and of the strips 47.

15 In the inner side of the window, at a distance from the bar or strip 44, and clear of the path of the lower sash 31, is located a horizontal strip 50 secured to the bottom member 20. At the upper end of the lower sash 31 is located the horizontal meeting rail 51, provided with an overhanging inclined outer surface, see Figs. 5 and 11.

20 To hold the lower sash in various inclined positions, I have provided an adjusting and locking device of the same character as disclosed in my earlier application above referred to. A brief description of said device will therefore be sufficient. Such device comprises a longitudinally 25 slotted bar 52 pivoted to one of the strips 28 to swing about a horizontal axis 53 and along the slot of the bar is movable an extension bar 54, connected with the bar 52 by a universal joint, and provided at its free 30 end with a ball-shaped enlargement 55 adapted to enter a key-hole slot 56 in a plate 57 secured to the upper edge of the lower sash 31. The bars 52, 54 are curved instead 35 of being straight as in my earlier application, but in other respects the construction and operation of this adjusting and locking device are substantially the same as in said application.

40 The upper sash 58 is narrower than the lower sash 31, and fits between the strips 27 and 47 (see Fig. 4), being guided for vertical movement at the upper portion of the window, by metal strips 59, projected inwardly from the strips 27 into vertical 45 grooves in the outer face of the upper sash 58. At its upper edge said sash has a groove 60 similar to the groove 43 and adapted to fit a horizontal top bar 61 similar to the bar 44. The sash 58 is cut out, 50 as at 62, to form channels for the chains 63 which are attached at the bottom of the sash in the same way as the chains 33 and pass over pulleys 64 to the corresponding sash weights 65. It will be seen (see Fig. 55 4) that the upper sash is narrower than the space between the two strips 46, and may therefore swing between them as explained below. At its lower edge the upper sash 58 has a meeting rail 66 with an inclined 60 surface adapted to engage the corresponding

surface of the meeting rail 51 of the lower sash (Fig. 11). The upper sash also has a plate 67 projecting inwardly at the bottom of the meeting rail 66 and adapted to engage the horizontal lower surface of the meeting rail 51. The panes of the sashes 31 and 58 are designated by 68 and 69 respectively.

65 At its lower end, each of the strips 47 has a vertical slot 70 (Figs. 10, 12 and 13) 75 in which is adapted to slide up and down a stop member 71, provided with an upright slot 72 through which extend the stationary pins 73. These pins in connection with the slot 72 limit the movement of the stop 71 in both directions, the upper inactive position being shown in Fig. 10 (see also dotted lines in Figs. 11 and 12) while the lower operative position of the stop is shown in Figs. 12 and 13. The lower ends 74 of the two 80 stops 71 may be bent horizontally, toward each other.

85 In the normal closed position of the window (Fig. 1) the upper sash 58 makes a tight or at least windproof joint with the bar 61 at the groove 60. Similarly, the lower sash 31, at its bottom, has a windproof joint where the bar 44 projects into the grooves 43 of said sash, and the strip 50 furnishes an additional barrier engaging the inner face of the sash at its bottom. The board 48 is in its lower position shown in Figs. 2 and 5, and thus conceals the existence of the cavity or chamber 25; this board might be omitted, since its only purpose is 90 to conceal the unsightly opening at the bottom of the chamber 25 which would otherwise be exposed to view whenever the lower sash has its top below said chamber. With the window closed, the meeting rails 51, 66 95 and the plate 67 are in engagement as in Fig. 11, so as to secure a tight joint at this point also. The locking bolts 41 are retracted (Fig. 12), so as to leave the lower sash 31 free to move up and down, and the stop members 71 are in their raised position (full lines in Fig. 10, and dotted lines in Figs. 11 and 12). I may here remark that the mere act of raising the upper sash to the closed position will cause the stop members 71 to be raised by contact with the plate 67, the meeting rail 66 being cut away at each side (see Fig. 10) so as to clear the stop member 71 and the strip 47. In the 100 particular embodiment illustrated, the raising of the upper sash 58 to its uppermost position will not bring the stop members 71 entirely to the uppermost position shown, but a slight additional upward movement will have to be given to the stop members 71 105 manually to bring them to their uppermost or releasing position. This releasing position is such that when the upper sash 58 is 110 fully down (in contact with the bottom member 20) this being the position shown in 115 120 125 130

Figs. 12 and 13, the stop members 71 in their releasing position will clear the upper edge of said sash, and since the strips 47 stop short of said upper edge, the sash will then be able to swing into the building in the manner indicated in Fig. 6, and the outer surface of the pane 69 may thus be cleaned without danger by bringing the sash either to an approximately horizontal position 12 (with the outer pane surface uppermost) or to an inverted vertical position, with the plate 67 at the top and the normally outer surface of the pane facing toward the inside of the building. It will be noted that 18 this inward swinging of the upper sash 58 can be effected without bringing the hinged strips 29 out of their normal position (Fig. 3). This is possible for the reason that the upper sash 58 is narrower than the space between the two strips 29, as will be obvious from Figs. 3 and 4.

In order to enable the upper sash 58, when fully lowered as just described, to be swung inwardly, the lower sash 31 must be 23 raised to a position (Figs. 6, 12 and 13) in which it clears the path of the upper sash 58 for such inward swinging. The chamber 25 is provided for the purpose of giving the lower sash 31 the extra upward travel required to accomplish this result. In bringing the sash 31 to this position, Fig. 6, the board 48 is raised by the upper edge of the sash, but as soon as the sash is lowered, the board 48 will drop back to the normal position shown in Figs. 2 and 5.

When it is desired to clean the inner surface of the pane 69, the upper sash 58 is lowered fully as in Fig. 13, and the stop members 71 are preferably pulled down 40 fully as shown in Figs. 12 and 13 so as to block the inward swinging of said sash. This is to guard against the possibility of accidents that might occur if the stop members 71 were left in their uppermost position 45 and the cleaner were called away from the window, when a gust of wind might cause the sash to pass to the position shown in Fig. 6 and to drop inward. If then the sash 58 is raised fully, its plate 67 will raise the stop members 71 somewhat, but not fully, so that manual operation, as described above, 50 will be required to bring the stop members to the releasing position Figs. 10 and 11.

The inner surface of the pane 68 of the 55 lower sash 31 will be cleaned in the usual manner. To clean the outer surface of said pane, the hinged strips 29 will be swung open as indicated in Fig. 5 (see also dotted lines in Fig. 3 and at the left of Fig. 7), 60 thus clearing the path for the inward swinging of the lower sash (when in its lowermost position) in the same manner as described above with reference to the upper sash. That is to say, the sash may either 65 be swung inward, its bottom edge forming

a pivot, until the sash is about horizontal, with the outer surface of the pane 68 on top; or, together with such swinging movement, the lower edge of the sash may be slid upward until the sash 31 is vertical, but inverted, with the normally outer surface of the pane 68 facing inward.

When it is desired to open the lower sash 31 slightly, for ventilation, as shown in Fig. 5, the said sash being in its normal lowered position, the ball-shaped enlargement 55 of the bar 54 is introduced into the wide end of the key-hole slot 56 and swung laterally therein to the other end of said slot. The sash 31 may then be opened within the limit 75 permitted by the maximum extension of the extensible bar 52, 54. Whenever the lower sash 31 is intended to swing about a stationary fulcrum at its lower edge, as when it is opened for ventilation, or into a substantially horizontal position for cleaning, the two locking and pivot bolts 41 are projected 80 as in Fig. 8 and engaged with the recesses 42.

Various modifications may be made without departing from the nature of my invention as set forth in the appended claims.

I claim:

1. In a window, a relatively wide sliding sash and guides therefor, a relatively narrow sash adapted to pass between the guides 95 of the first-named sash when the latter is in one of its extreme positions, means for freely suspending said sashes pivotally connected upon a horizontal axis to the lower extremities of said sashes, and guides for the second-named sash, terminating in a position which permits said sash when moved upon its pivotal connection to freely pass between the guides of the first-named sash when the two sashes are in opposite extreme positions, 100 whereby said second named sash may be entirely reversed upon its pivotal connection without removing said first named sash.

2. In a window, a frame having continuous upright outer guide strips and strips projecting inwardly from said guide strips at their upper portions only, middle guide strips facing said outer guide strips at said upper portions only, an upper sash arranged to travel in engagement with the opposing faces of said outer and middle guide strips, and having grooves in its outer surface to receive said projecting strips, the height of said sash being less than the distance from the lower end of the middle guide strips to 110 the bottom of the window opening, additional strips projecting inwardly from the lower portions of the middle guide strips and extending therefrom down to the bottom of the window opening, inner guide strips facing said middle guide strips and said additional projecting strips, the lower portions of said inner guide strips being movable to leave a clear space under their 115 upper portions, and a lower sash movable 120

between said inner and middle guide strips and having grooves in its outer surface to receive said additional projecting strips, the height of said lower sash being less than the length of said movable portions of the inner guides.

3. In a window, a frame having continuous upright outer guide strips and strips projecting inwardly from said guide strips
10 at their upper portions only, middle guide strips facing said outer guide strips at said upper portions only, an upper sash arranged to travel in engagement with the opposing faces of said outer and middle guide strips, and having grooves in its outer surface to receive said projecting strips, the height of said sash being less than the distance from the lower end of the middle guide strips to the bottom of the window opening, additional strips projecting inwardly from the lower portions of the middle guide strips

and extending therefrom down to the bottom of the window opening, inner guide strips facing said middle guide strips and said additional projecting strips, the lower portions of said inner guide strips being movable to leave a clear space under their upper portions, the distance between the inner guide strips being greater than the width of the upper sash, and greater than the distance between the middle guide strips, and a lower sash, wider than the upper sash, movable between the said inner and middle guide strips and having grooves in its outer surface to receive said additional projecting strips, the height of said lower sash being less than the length of said movable lower portions of the inner guides.

In testimony whereof I have affixed my signature.

JACOB WEBER.
